MEASURING CUP

Edwin B. Feldman, P.O. Box 2665, Atlanta, Ga.

Filed Mar. 17, 1965, Ser. No. 84,332

Term of patent 14 years

(Cl. D44—9)

Fig. 1.

Fig. 2.

Fig. 4.

Fig. 3.

FIG. 1 is a perspective view of a measuring cup showing my new design, the essential features of which are shown in full lines;

FIG. 2 is a sectional view taken on line 2—2 of FIG. 1;

FIG. 3 is a perspective view of a measuring cup showing a modification of my new design wherein all indicia are omitted therefrom; and

FIG. 4 is a perspective view of a measuring cup showing a modification of my new design wherein all indicia are omitted and a pouring lip is provided at the upper edge at the center line of one of the upright legs.

I claim:

The ornamental design for measuring cup, as shown and described.
